UNITED STATES PATENT OFFICE.

JEREMIAH N. FOUTZ, OF ANAHEIM, CALIFORNIA.

INSULATOR.

1,042,902.

Specification of Letters Patent.

Patented Oct. 29, 1912.

Application filed December 21, 1911. Serial No. 667,061.

To all whom it may concern:

Be it known that I, JEREMIAH N. FOUTZ, a citizen of the United States, residing at Anaheim, in the county of Orange, State 5 of California, have invented certain new and useful Improvements in Insulators; and I do hereby declare the following to be a full, clear, and exact description of the invention, such as will enable others skilled in 10 the art to which it appertains to make and use the same.

This invention relates to improvements in insulators, and has for its object to provide a device of this character wherein the wire 15 may be easily and effectually connected thereto and removed therefrom.

A further object of the invention is to so construct the same that it may be quickly attached to and removed from the pole arm, 20 or other support.

With these and other objects in view, the invention consists in certain novel features of construction, combination and arrangements of parts as will be hereinafter fully 25 described and claimed.

In the drawings: Figure 1 is a side elevation of the device showing the same applied to a portion of a pole arm. Fig. 2 is a vertical sectional view of a portion of the same. 30 Fig. 3 is a top plan view of the insulator. Fig. 4 is a sectional view taken at right angles to Fig. 2.

Referring to the drawing, the numeral 1 designates the body of the insulator the 35 same being formed preferably from glass, it being of course understood that any other suitable material may be employed.

Protruding from the under side of the body 1 is a threaded flange 2, said flange 40 being adapted for detachable connection with the threaded metallic sleeve 3. The sleeve 3 has an opening 4 formed in the bottom thereof, thus producing a flange 5, said flange being adapted to rest upon the upper 45 face of the arm 6. A disk 7 is provided and is placed within the sleeve 3, the same resting upon the flange 5. A central perforation is formed in the disk 7, as indicated at 8, and through which is passed a screw 9, 50 said screw being for the purpose of firmly forcing the disk 7 against the flange 5, thus securely holding the sleeve 3 upon the arm 6.

A transverse groove 10 is formed in the body 1, and has one of its walls formed with a concaved recess 11, and its other wall with 55 a downwardly inclined shoulder 12, said shoulder being of such thickness as to project a short distance within the recess 11, the base 13 of the shoulder 12 being spaced slightly above the base of the groove 10. 60 Both ends of the base of the groove 10 open into the annular groove 14 formed in the body 1, so that the conductor wire 15 may be bent at right angles to the groove 10 and seated partially within the groove 14, or 65 the conductor wire may be wound completely around the body portion and in the groove 14, thus permitting the wire 15 to extend at right angles to the groove 10, or the same may be bent upon itself when it is 70 desired to string a wire to a branch office or the like. From this construction it will be seen that the conductor wire 15 may be forced against the shoulder 12, said shoulder in turn forcing the wire into the recess 11 75 until the same passes from the shoulder, whereupon it will then engage under the base of the shoulder and upon the base of the groove 10. When it is desired to remove one of the insulators for any purpose, it is 80 only necessary that the wire 15 be moved laterally until it frees the base of the shoulder 12, and at which time it will then pass freely through the recess 11 and out of the groove 10. 85

What is claimed is:

The combination with a support, of an insulator, having a threaded flange, a sleeve having threads formed therein, a flange formed in the bottom thereof, a disk having 90 a central perforation, said disk being adapted to rest upon the flange, a screw passing through the perforations of the disk and in engagement with the support for firmly holding the sleeve upon the support, said 95 threaded flange being adapted for detachable connection with said sleeve.

In testimony whereof, I affix my signature, in presence of two witnesses.

JEREMIAH N. FOUTZ.
